UNITED STATES PATENT OFFICE.

HERMAN THEODORE ROSEEN, OF WALKERTON, INDIANA.

DIPPING DEVICE.

1,150,065.

Specification of Letters Patent. Patented Aug. 17, 1915.

Application filed June 11, 1914. Serial No. 844,438.

To all whom it may concern:

Be it known that I, HERMAN T. ROSEEN, a citizen of the United States, residing at Walkerton, county of St. Joseph, and State 5 of Indiana, have invented certain new and useful Improvements in Dipping Devices, of which the following is a specification.

This invention relates to article conveying devices, and may be more particularly associated with that class of devices used in 10 conveying glass articles and supporting the same during the dipping process, incident to cut glass manufacturing.

The primary object of my invention is to 15 provide means whereby a number of glass articles, such as tumblers or bowls may be easily and conveniently picked up and supported during the dipping process.

A further object of my invention is to 20 provide in a device as above briefly set forth, improved means for releasing the articles supported simultaneously.

A still further object of my invention is to provide a device for the purposes stated 25 wherein the hands of the operator may be protected from the acid during the dipping process.

A still further object of the invention is to provide means whereby the operative 30 parts of the mechanism for supporting the articles will be protected from contact with the acid.

More particularly, my invention has further for an object to provide means whereby 35 articles of various sizes may be supported and carried.

A still further object of the invention is to provide a device of this character which shall be simple in construction, cheap in 40 manufacture, which is easy and simple in operation, and yet which is so arranged as to securely hold the articles to be conveyed without danger of dropping or breaking any of such articles.

With these objects in view together with 45 others which will appear as the description proceeds, my invention consists in the novel combination and arrangement of parts, all as will be more fully described hereinafter, 50 and more particularly pointed out in the appended claims.

My invention will be best understood with reference to the accompanying drawings, in which:

Figure 1 is a longitudinal section through 55 an article conveying device constructed in accordance with my invention; Fig. 2 is a top plan view of the same, and, Fig. 3 is a bottom plan view of the device.

Referring now more particularly to the 60 drawings, 4 represents generally a box-like structure, comprising ends and sides 5 and 6 respectively, and a bottom 7. Arranged within this box-like structure and secured to the bottom thereof, is a series of pipes 8, 65 the same being shown in the present instance extending lengthwise of the structure, but it is to be understood that these pipes may be arranged within the box-like structure in any desired or preferred manner. At various intervals in the length of the pipes 8 and communicating therewith are nozzles 9. These nozzles extend through the bottom of the box-like structure and are secured in position by a suitable nut 10, binding the same securely within the bottom 4. The ends 11 of the nozzles extend slightly 70 beyond the outer surface of the bottom 7. A cross pipe 12 connects with each of the pipes 8, and is provided with a valve 13. 75 A nipple 14 connects the valve 13 with a duct 15, formed preferably of flexible hose or the like, and a quick detachable member 15' may be provided upon the end of the duct to cooperate with the nipple 14 to facilitate sure and speedy attaching and detaching of the device to the duct. This hose, 80 it is to be understood, may be connected to a pump or other suitable means, not shown, for creating suction. 85

It is obvious from the above description that upon operation of the pump or other devices in connection with the duct 15, suction will be created at each of the nozzles, and it is obvious that this suction may be 90 controlled by the valve 13.

The outer face of the bottom 4 of the box-like structure is provided with a layer or thickness of resilient material, such for instance as rubber, 16, and the sides, ends, and 100 bottom of the device are then covered with a substantially thin sheet of rubber or other

similar resilient material 17. By providing the entire bottom surface of the box-like structure with a resilient covering, it is obvious that dishes or glass vessels of larger dimensions than the ordinary glasses, tumblers or the like may be efficiently supported. In such case the vessel of larger dimension would be positioned to extend over several of the nipples, as shown by dotted lines in Fig. 3, and it is apparent that air, after a partial vacuum has been created, will be prevented from gaining access to the interior of the vessel in the same manner as has been described in connection with the smaller articles.

Handles 18 are provided preferably upon the ends of the device in order that the same may be conveniently lifted and carried. These handles as shown, are positioned upon the interior of the box-like structure in order that the hands may be protected during the process of subjecting the articles carried by the device to acids or other mixtures.

The operation of the device is very simple. The articles which are adapted to be conveyed or supported by the device, such, for instance, as tumblers or bowls, an illustration of one of the former classes of articles being shown in Fig. 1 at 18', are positioned with their open ends over each of the nozzles 11 upon the bottom 4 of the structure. The valve 13 is then opened and the pump to which the duct 15 is connected removes the air from within the pipes and also from the articles positioned over the nozzles. As a partial vacuum is created within the glasses or bowls, the valve 13 may be closed, and the duct or flexible hose 15 may be disconnected from the nipple 14 connected to the valve. The device may then be conveyed to the tank containing the solution and dipped, and the danger of the articles secured to the bottom of the box-like structure by atmospheric pressure becoming loosened therefrom is obviously small. After the dipping operation the device may be relieved of the clinging articles by opening the valve 13 to relieve the atmospheric pressure within the pipes. By providing the double thickness of rubber or other similar flexible material upon the bottom 4 of the box-like structure it is apparent that the danger of admission of air between the upper edges of the articles and the bottom of the device is decidedly small. This double thickness permits of a tight joint adjacent the rim of the articles despite the fact that there may be slight irregularities or nicks in the said edges. It is also apparent that by providing a rubber coating for the entire outer surface of the box-like structure, there is little danger of water or acid gaining access to the interior thereof. The body of the box-like structure may be formed of any desired ma-

terial, and although wood may be used in the construction, I find a light, substantially thin sheet metal most practical.

I claim:

1. A device of the class described comprising a box-like structure, a layer of resilient material on the bottom of said structure, a rubber cover inclosing said resilient material and the sides and ends of said box, a series of pipes within said structure, a plurality of nozzles connected to said pipes and extending through the bottom of said box and said resilient material and rubber cover to communicate with the exterior thereof, a duct communicating with said pipes, and a valve in said duct, substantially as described. 70 75 80

2. A device of the class described comprising a box-like structure, a series of pipes within said structure and a plurality of nozzles connected to said pipes and extending through the bottom of said box to communicate with the exterior thereof, means for controlling the air pressure within said pipes, and handles upon the inner surfaces of the ends of said box-like structure, substantially as described. 85 90

3. A device of the class described comprising a box-like structure, a layer of resilient material secured upon and coextensive with the bottom of said box, a series of pipes within said structure, a plurality of nozzles connected to said pipes and extending through the bottom of said box and resilient material to communicate with the exterior thereof, a duct communicating with 95 100 said pipes and a valve in said duct, substantially as described.

4. A device of the class described comprising a box-like structure, a series of pipes within said structure and a plurality of nozzles connected to said pipes and extending through the bottom of said box to communicate with the exterior thereof, a valve in connection with said pipes, a duct, and a quickly detachable member upon the 105 110 end of said duct for connecting the latter with said valve, substantially as described.

5. A device of the class described comprising a box-like structure, a series of pipes within said structure, a nipple communicating with and common to all of said pipes, a valve in said nipple for controlling the pressure of air within said pipes, and each of said pipes having a plurality of nozzles extending therefrom through the bottom of 115 120 said box to communicate with the exterior thereof, substantially as described.

6. A device of the class described comprising a box having a bottom, ends and sides, a layer of resilient material on the 125 bottom of said box, a cover of impervious material covering said layer and the sides and ends of said box, a series of pipes in

said box, a plurality of nozzles connected to said pipes and extending through said bottom to communicate with the exterior thereof, means for controlling the air pressure within said pipes, and handles secured upon the interior of said box, substantially as described.

In testimony whereof I have signed my name to this specification in the presence of two subscribing witnesses.

HERMAN THEODORE ROSEEN.
